(57) **CLAIM**

What is claimed is the ornamental design for a trivet, as
shown and described.

DESCRIPTION

FIG. 1 is a perspective view of a trivet showing a new
design;

FIG. 2 is a top view of the trivet of FIG. 1;

FIG. 3 is a side view of the trivet of FIG. 1;

FIG. 4 is a front view of the trivet of FIG. 1; and,

FIG. 5 is a bottom view of the trivet of FIG. 1.

The broken lines in the drawing depict portions of the trivet
that form no part of the claimed design.
